UNITED STATES PATENT OFFICE.

CHARLES T. WESTLAKE, OF ST. LOUIS, MISSOURI, ASSIGNOR TO DAVIS LOCOMOTIVE WHEEL COMPANY, OF ST. LOUIS, MISSOURI, A CORPORATION OF DELAWARE.

LOCOMOTIVE BUFFER-BEAM.

No. 893,211.

Specification of Letters Patent.

Patented July 14, 1908.

Application filed March 2, 1908. Serial No. 418,907.

To all whom it may concern:

Be it known that I, CHARLES T. WESTLAKE, a citizen of the United States, residing at St. Louis, in the State of Missouri, have 5 invented a new and useful Improvement in Locomotive Buffer-Beams, of which the following is a specification.

My invention relates to a metallic buffer-beam or end sill for a locomotive or car 10 underframe, and is in the nature of a modification of the buffer-beam described in the Letters Patent of the United States granted to me May 21, 1907, Number 854,131, in which the diagonal struts diverge from the 15 front member of the beam to their junction with the rear member thereof; and my invention has for its object to produce a strong, rigid, and durable buffer-beam having its members specially arranged for insuring 20 direct transmission therethrough of the buffing and other concussive stresses to the longitudinal beams or sills of the under-frame.

It consists essentially in reversing the direction of the diagonal struts above referred 25 to, combined with other features of novelty as hereinafter described and claimed, reference being had to the accompanying drawing forming part of this specification, whereon,

Figure 1, is a top plan view of a preferable 30 form of my improved buffer-beam; Fig. 2, a vertical transverse section thereof on line 2, 2, in Fig. 1; Figs. 3 and 4, views corresponding to Figs. 1 and 2 respectively, and Fig. 5, a view corresponding to Fig. 1, showing constructive modifications of the beam.

Like letters and numerals of reference denote like parts in all the figures.

Referring to Figs. 1 and 2, *a* represents 40 my improved buffer-beam or end sill which is preferably composed of cast steel integral throughout, the body thereof, or beam proper, being preferably, I-shaped in cross section, having when assembled, its flanged members 1 and 2 vertically arranged, the 45 rear member 1 being adapted to bear against the ends of the longitudinal beams *b* of the engine frame (or sills of the car frame as the case may be) to which the buffer-beam *a* is fixed in the present case, by bolts 3 passed 50 horizontally and transversely through the beams *b*, and through brackets 4 and 4' which project at right angles from the outer face of the rear member 1 and are adapted to bear respectively, against the outer and 55 inner upright faces of the longitudinal beams

b, the outer brackets 4 being preferably riveted to the rear member 1, and the inner brackets 4' integral with the latter and united to each other by a horizontal rib or web 5 which projects rearwardly from the member 1 and forms a brace to the beams *a* and *b* thereat. The opposite or front member 2 of the buffer-beam *a* is preferably parallel to the rear member 1 for a suitable distance on each side of the middle of the beam *a*, or longitudinal center of the engine or car frame (in the present case to the extent of the distance between the outer upright faces of the longitudinal beams *b*) and thence inclined toward and united with each end of the rear member 1, where the beam *a* is formed preferably with an inside and outside push pole pocket or concavity 6.

Through the horizontal web 7 which unites the rear and front members 1 and 2 together, 75 are formed openings 8, 8', 8'', the openings 8 being separated from each other at the middle of the beam *a* by a portion of the web 7 which is intersected at right angles by a rib 9 coinciding with the longitudinal center of the frame and uniting with the rear and front members 1 and 2, to which, with the said portion of the web 7, it forms a middle intermediate straight strut *c*. Similarly, each opening 8 is separated from its adjacent opening 8' by an inclined portion of the web 7 which is intersected at right angles by a rib 10, uniting with the rear member 1, preferably, at the junction thereof with the middle strut *c*, and with the front member 2, preferably, opposite to the end of the corresponding longitudinal beam *b*, and thereby forms with the said inclined portion of the web 7 a diagonal strut *d* diverging from the rear member 1 to the front member 2 of the beam *a*. Furthermore, each opening 8' is separated from its adjacent end opening 8'' by a portion of the web 7 which is intersected at right angles by a rib 11 coinciding with the longitudinal center of the corresponding longitudinal beam *b*, the rib 11 uniting with the rear member 1, and with the front member 2, preferably at the junction thereof with the diagonal strut *d*, and thereby forming with the last named portion of the web 7 a straight intermediate strut to the members 1 and 2 opposite to the end of the said beam *b* and parallel to the middle strut *c*.

By the above construction the "buffing" stress on the front member 2 of the beam *a* is

transmitted by compression through the middle strut *c* to its junction with the diagonal struts *d*, thence by tension through the latter to their junction with the side struts *e*, and thence by compression through the struts *e* directly to the end portions of the longitudinal beams *b* of the frame in alinement therewith; that is to say, by transmitting the "buffing" stress tensionally through 10 the diagonal struts *d*, in lieu of by compression as in the said patent, the tension of the rear member 1 between its points of support in that case is eliminated, and the resultant stress communicated to the longitudinal 15 beams *b* in a more direct line therewith and to better advantage for obtaining the maximum resistance of the beam *a* with the least amount of material. When "pulling" on the beam *a* the reverse effect is produced, the 20 stress being transmitted by tension through the strut *c*, thence by compression through the diagonal struts *d*, and thence by tension through the struts *e* and rear brackets 4 and 4' to the bolts 3 and end portions of the longitudinal beams *b*.

In the modification shown in Figs. 3 and 4 the buffer-beam *a'* in lieu of being I-shaped as before described, is box-shaped in cross section having its top member solid throughout, and its lower member, which in the present case is flush, but may be above the bottom of the beam *a'*, formed with openings therethrough corresponding to the openings 30 8, 8', 8'', and having their separating portions 35 of metal and the reinforcing ribs thereof, adapted to form compression and tension struts or members arranged in a similar manner and on the same principle as the struts *c*, *d*, and *e*, in Figs. 1 and 2. Or if desired the 40 top member may be formed with intersecting ribs similar to the ribs 9, 10, and 11, with or

without openings corresponding to the openings 8, 8', and 8''.

In the modification shown in Fig. 5 the rear member 1 of the beam *a''*, in lieu of being straight for its entire length, is formed with a rectangular offset 1' which extends rearward along and between the longitudinal beams *b* of the frame *a''*, the lateral portions of the offset 1', which correspond to the inner brackets 4' before described, being adapted to bear against the inner faces of the beams *b* to which, and to the outer brackets 4, they are fixed by bolts in the same manner as in Figs. 1 and 2, the struts *c* and *d* in this 55 construction being correspondingly extended rearward from the front member 2 to their junction with the offset 1' as shown.

What I claim as my invention and desire to secure by Letters Patent is:—

A buffer-beam for a locomotive engine or car underframe, comprising a rear member adapted to bear against and to be fixed to the longitudinal beams of the said frame, a front member opposite to and spaced apart from the rear member, a strut uniting the said members together in alinement with the said longitudinal beams and the longitudinal center of the said frame respectively, and diagonal struts, one on each side of the said center, 70 uniting the said members together at the junction therewith, or thereabout, of the first named struts, substantially as described and for the purpose set forth.

In testimony whereof I have signed my name to this specification in the presence of two subscribing witnesses.

CHARLES T. WESTLAKE.
